EXEMPLARY CLAIM

1. A fuze for exploding projectiles and the like in proximity to a target, comprising, means for generating radio frequency waves, means for propagating said generated waves through the space intervening between the projectile and the target, a portion of said propagated waves being reflected back by said target toward said propagation means, means connected to said propagation means for simultaneously detecting said generated waves and said reflected waves to provide a signal for firing said fuze, said detecting means being sensitive to said reflected waves only in the presence of said generated waves, a variable impedance connected to said wave generating means, and means for varying said impedance from a relatively high value to a relatively low value thereby terminating the operation of said wave generating means to render said detecting means insensitive both to reflected waves and to spurious waves.

PULSE DOPPLER-RADIO PROXIMITY FUZE

This application is divided from co-pending application Ser. No. 210,851, filed Feb. 14, 1951, for Pulse Doppler-Radio Proximity Fuze.

The present invention relates to a pulse doppler-radio proximity fuze, and particularly to a pulse fuze protective system utilizing a pulse forming circuit to obtain impulses at a convenient recurrence rate to cause radiation of signal impulses.

The advent of the radio proximity fuze greatly increased the utility and reliability of explosive projectiles, particularly it made it possible for explosive projectiles to be accurately exploded within the optimum range of any given target. Because of the increased effectiveness of gunnery resulting from the use of the radio proximity fuze many means have been proposed to counteract or decrease its effectiveness. For example, it has been proposed to create simulated reflecting surfaces or pseudo targets to cause explosion of the projectile at a safe distance from the actual target. However, the most effective anti-proximity fuze device has been a repeater jammer device. The repeater jammer system operates by receiving the radiated signal from the proximity fuze, amplifying the signal, and re-radiating it so that the re-radiated signal is received back by the fuze in exactly the same manner as a properly reflected radiation from a normal target. In this manner the jammer is able to produce premature explosions of proximity fuzed missiles without any appreciable danger to it or to the actual targets.

For a repeater jammer to be effective as an anti-proximity device, it is necessary that the re-radiated signal be returned to the proximity fuze while the proximity fuze is in an active receiving condition. If it is possible to render the fuze inactive at the time the jammer signal is received, then no damage could be caused thereby, consequently if the fuze can be operated at an on-and-off condition, or preferably by aperiodic or periodic pulses of sufficient duration so that the first radiated waves would only have time to be reflected from the target surface at its maximum permissible distance, then the jammer, which would be at a further distance, would send back its re-radiated signal during an inactive interval of the proximity fuze.

The heretofore known proximity fuzes have emitted continuous radiation which was easily received and re-radiated by the repeater jammer.

The present invention provides a pulsing system in which a thyratron relaxation oscillator is utilized to provide impulses which control the operation of an oscillator circuit to which is coupled a gated detector system. In this manner the thyratron oscillator circuit produces relatively short operating pulses of the proximity fuze oscillator system; preferably the pulses are of relative short duration and have a relatively long off period so that the duty cycle of the oscillator is very low, thus making it substantially impossible for a repeater jammer to produce any undesirable jamming effects, and because of the use of the gated detector circuit the detector system is completely unresponsive except during the short interval during which the oscillator is operative.

It is accordingly an object of the invention to produce a radio proximity fuze substantially immune to signals from a repeater jammer.

It is a further object of the invention to provide a radio proximity fuze having spaced apart pulses of radiated signals.

Another object of the invention is to provide a thyratron circuit for controlling the operation of a proximity fuze.

It is still another object of the invention to provide a proximity fuze which is inoperative during a large portion of its duty cycle.

10 Other objects and many of the attendant advantages of this invention will be readily appreciated as the same becomes understood by reference to the following detailed description when considered in connection with the accompanying drawings wherein:

15 FIG. 1 is a circuit diagram of a proximity fuze oscillator involving the invention;

FIG. 2 is a graphic illustration of the positive pulse control and the resulting signal pulses;

20 FIG. 3 is a circuit somewhat similar to FIG. 1 but showing a modification; and

FIG. 4 is a graphic illustration showing negative biased pulses.

25 In an exemplary embodiment of the invention according to FIG. 1, the fuze system consists of an oscillator 10 controlled by a pulse generator or pulse forming circuit 11 and a clipper 12 for determining the length of the pulse. The reflected signals are received through the oscillator 10 by a gated detector 13.

The pulse forming circuit 11 is in the nature of a 30 relaxation oscillator receiving energy from any source such as a battery through an impedance 14 to charge a capacitor 15 which discharges through a thyratron 16 having a grid 18. The system takes advantage of the fact that at the instant of discharge in a thyratron the grid 18 becomes momentarily positive.

35 The positive potential of the grid 18 is utilized to produce pulse operation of the oscillator 10 by impressing the potential of said grid on the plate 19 of the triode oscillator tube 20 to serve as the power source for the oscillator 10. The oscillator 10 can of course be any suitable type of oscillator but it is desirable to use simple and dependable circuits requiring a small number of components and is shown as having a tank coil 22 connected between an antenna 21 and ground with suitable coupling to the grid 23 and cathode 24 of the triode or oscillator tube 20. The usual high frequency bypass capacitor 25 is connected across the potential source or from grid 18 to ground.

40 The clipper 12 is provided to control the length of the pulse and consists of a gas filled triode clipper tube 30, which is connected between the power supply of the oscillator 10 and ground, and a slight time-delay occurs after the initiation of the impulse before the clipper tube 30 shorts out or grounds the power supply to the oscillator 10, so that the oscillator 10 is active only during the short interval during which power is supplied to the plate 19 of tube 20.

45 The detector 13 includes a diode detector tube 31 which is connected through the oscillator 10 so that it can receive signals only during the interval when the oscillator 10 is operating. The output of the detector 13 is connected to terminal 32 of a suitable amplifying device (not shown) and is used to trigger or detonate the squib or primer of the explosive carried by the projectile.

50 The mode of operation of this modification can most conveniently be explained by reference to FIG. 2, in which the control impulses received from the grid 18 of

the thyratron tube 16 appear as positive pulses 34. As soon as the positive pulse 34 is applied to the oscillator 10, said oscillator output begins to build up, and after a short build up period the radio frequency pulse, indicated at 35, will be of sufficient strength to be radiated. The full strength radiation should be emitted for a sufficient interval so that the first full-wave 36 emission will have time to return to the oscillator 10 from targets at the maximum permissible distance before the end of the oscillation pulse, shown at 37.

The pulse 34 attenuates rather rapidly but would produce an oscillation pulse 35 of considerable length, and it is generally desirable to utilize the clipper 12 to produce a sharp cut off 38 on pulse 34 and preferably the cut off 38 establishes the maximum radius of sensitivity. For example, if the maximum radius of sensitivity is desired to be 200 feet, then cut off 38 is adjusted so that wave 36 would be reflected from an object 200 feet away and return at or just before the end 37 of the radiated pulse 35.

Any radiation from pulse 35 that would have been picked up by a repeater jammer will be re-radiated, but will arrive after the end 37 of the pulse 35 so that it cannot be received by the gated detector 13, and consequently can do no harm to the fuze.

Instead of utilizing a positive impulse from the pulse forming circuit 11 to provide the power for the oscillator 10, it is likewise permissible to utilize the negative impulses, which occur at the plate of the thyratron during each conducting interval in a thyratron tube, to bias a short-circuiting or keyer tube 9 to inoperative i.e. non-conductive condition. Such a circuit is disclosed in FIG. 3, wherein oscillator 10 has connected in shunt therewith a triode tube 40 which, when conducting, has a sufficiently low impedance to substantially short-circuit the oscillator 10 and, therefore, to prevent any radiatable signals. Preferably the short-circuiting tube 40 is positively biased to be normally conducting and therefore to maintain the oscillator 10 inoperative. As seen in FIG. 4, the negative impulse 41 of the relaxation oscillator 11 is applied to the grid 42 of the short-circuiting tube 40 and depresses the voltage at the grid 42 to a value where the tube 40 becomes non-conducting, at which time the oscillator 10 will become operative and radiate a pulse 35 of radio frequency energy. The effect of either of these systems is to produce short pulses 35 of radiated energy interposed between relatively long intervals when no energy is radiated. Obviously, if at the beginning of pulse 35 the projectile and its fuze had arrived within the immediate vicinity of any target object, said target object would, of course, reflect said pulse to the fuze and cause immediate operation thereof.

In the presently used proximity fuzes radio frequency signals at a frequency between 150 and 200 megacycles and pulses 35 at the rate of between 10,000 and 15,000 pulses per second have proven quite satisfactory. Obviously this can be varied as may be desirable by providing the suitable components for the relaxation oscillator circuit.

Obviously, many modifications and variations of the present invention are possible in the light of the above teachings. It is therefore to be understood that within the scope of the appended claims the invention may be practiced otherwise than as specifically described.

What is claimed is:

1. A fuze for exploding projectiles and the like in proximity to a target, comprising, means for generating radio frequency waves, means for propagating said

generated waves through the space intervening between the projectile and the target, a portion of said propagated waves being reflected back by said target toward said propagation means, means connected to said propagation means for simultaneously detecting said generated waves and said reflected waves to provide a signal for firing said fuze, said detecting means being sensitive to said reflected waves only in the presence of said generated waves, a variable impedance connected to said wave generating means, and means for varying said impedance from a relatively high value to a relatively low value thereby terminating the operation of said wave generating means to render said detecting means insensitive both to reflected waves and to spurious waves.

2. A fuze as claimed in claim 1, wherein said variable impedance comprises an electron tube and said means for varying the impedance comprises a pulse generator for supplying control impulses to said tube to vary the tube from a non-conductive to a conductive state.

3. A radio proximity fuze comprising, an oscillator for generating radio frequency waves, an antenna for propagating said generated waves through space and for receiving waves reflected from a target and propagated through space toward said antenna, a detector for rectifying said generated waves and said received waves, an output connection from said detector for utilizing the detector output to fire said fuze, an electron tube connected to said radio frequency oscillator to load said radio frequency oscillator into a non-oscillatory condition upon conduction of said tube, and a pulse forming oscillator for supplying control impulses to said tube to render said tube alternately conductive and non-conductive whereby said radio frequency oscillator is alternately transferred from a non-oscillatory condition to an oscillatory condition thereby affording said fuze protection against jamming by remotely situated radio transmitters.

4. A radio proximity fuze comprising, an oscillator including a resonant circuit and a first electron tube connected to said resonant circuit to maintain resonant oscillations therein, an antenna coupled to said resonant circuit to radiate oscillations generated by said oscillator and to receive the generated oscillations reflected from a target, a second normally conductive electron tube connected to said resonant circuit to damp oscillations in said circuit by conduction through said second tube, a detector connected to said antenna for rectifying both said radiated oscillations and said received oscillations to provide a signal for firing said fuze, and a relaxation oscillator for controlling the conduction of said second electron tube, said relaxation oscillator including a thyratron tube periodically supplying negative pulses to said second tube to render the same non-conductive and thereby undamp said resonant circuit.

5. A radio proximity fuze comprising, an oscillator including a tank coil, a first electron tube having cathode, grid, and plate electrodes, said cathode and grid electrodes being connected to said tank coil, a source of power connected to said plate, a ground circuit, a connection from said tank coil to said ground circuit, an antenna connected to said tank coil for radiating oscillations generated therein and for receiving the generated oscillations reflected from a target, a diode having one of its electrodes connected to said antenna, a capacitor connecting the other electrode of said diode to said ground circuit, an output connection to the junction of said capacitor and said electrode, a second electron tube

having cathode, grid, and plate electrodes, the cathode of said second tube being connected to said ground circuit and the plate of said second tube being connected to said tank coil, means for applying a bias voltage to the grid of said second tube to maintain the same

5

normally conductive, and means for periodically decreasing said bias voltage to render said second tube non-conductive, whereby the fuze is effectively protected against re-radiation jamming.
